Primary Examiner — Lakiya G Rogers*Assistant Examiner* — Carissa C Fitts(74) *Attorney, Agent, or Firm* — Haynes and Boone, LLP(57) **CLAIM**

The ornamental design for a handheld lighting device, as shown and described.

DESCRIPTION

FIG. 1 is a front, left, and top perspective view of a handheld lighting device showing our new design;

FIG. 2 is a rear, right, and bottom perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a front elevational view thereof; and,

FIG. 8 is a rear elevational view thereof.

FIG. 9 is a front, right, and bottom perspective view of the handheld lighting device having a knife blade deployed therefrom in response to an actuation of a sliding member. The broken lines in the drawings illustrate environmental features and form no part of the claimed design.
